H. W. TITGEN

TUYÈRE WIND BOX

Filed Feb. 12, 1926

Inventor:
Harry W. Titger,
by his Attorneys,
Howson & Howson.

UNITED STATES PATENT OFFICE.

HARRY W. TITGEN, OF PHILADELPHIA, PENNSYLVANIA.

TUYÈRE WIND BOX.

Application filed February 12, 1926. Serial No. 87,880.

My invention relates to furnaces and it has particular relation to tuyère wind-boxes. Heretofore, considerable difficulty has been experienced in the operation of cupola furnaces by reason of the fact that at times the metal backs up into the tuyère wind-boxes, filling the pockets thereof with molten metal. The subsequent removal of this metal is very difficult and requires a considerable amount of time and effort.

An object of my invention, therefore, is to provide a tuyère wind-box that shall be characterized by the absence of pockets and other recesses, so that if the molten metal should back up into the wind-box, no harm is done.

Another object of my invention is to provide a tuyère wind-box that shall be characterized by its simplicity of design, ease of construction and accessibility for purposes of repair,—the construction contemplating in particular a removable plate provided with a curved inner surface extending forwardly and upwardly from the furnace opening.

Other objects and applications of my invention, as well as details of construction and operation, whereby my invention may be practiced, will be apparent more fully hereinafter, when taken in connection with the accompanying drawings, wherein

Fig. 1 is a detail vertical sectional view of a furnace and associated wind-box embodying my invention.

Figs. 2 to 5, inclusive, are detail perspective views of certain parts of the structure of Fig. 1.

Referring to the drawing, a furnace wall 1 of usual design is provided with a tuyère opening 2, an outer end 3 of which communicates with a discharge end 4 of a tuyère wind-box 5. The tuyère wind-box 5 is provided with an elbow of L section 6, a lower end 7 of which constitutes the discharge end 4 of the wind-box and an upper end 8 of which is continued by means of a tubular tuyère extension 9 to a casing 10 forming the usual wind belt 11.

A feature of my invention is the provision of means, whereby such molten metal as backs up into the wind-box 5 through the air opening 2 is not retained and permitted to solidify, as in the constructions of the prior art. To this end, I provide the elbow section 6 (Figs. 2 to 5), which comprises a casting 12, having spaced substantially flat

side walls 13 and 14, the outer edges 15 and 16 of which are respectively provided with outwardly extending flanges 17 and 18. Inner edges 19 and 21 of the side walls 13 and 14 are interconnected by a curved wall 22, which is integral therewith and extends from lower vertical edges 23 and 24 of the side walls 13 and 14 to upper horizontal edges 25 and 26, respectively. The latter are provided with outwardly extending horizontal flanges 27 and 28, which are interconnected by a flanged portion 29 extending from an adjacent upper edge 31 of the inner wall 22. The side wall flanges 27 and 28 extend to the flanges 17 and 18 formed on the outerside wall edges 15 and 16, respectively.

The tubular elbow extension 9 is also provided with horizontally extending flanges 32, which may be supported on the adjacent horizontal flange portions 27, 28 and 29 of the elbow casting 12, and secured thereto by bolts 33, which extend through complementary apertures 34 in said adjacent flanges.

The casting 12 may be secured to the furnace wall 1 in any desired manner, such as, for instance, by providing the lower vertical edges 23 and 24 of the side walls 13 and 14 with outwardly extending flanges 35 and 36 respectively, and by further providing a lower edge 37 of the inner wall 22 with an upwardly extending flange 38, the several flanges being clamped against the furnace wall by bolts 39.

The retention of molten metal in the wind-box 5 may be further prevented by providing a curved outer wall 41 for the elbow casting 12 (Figs. 3 and 4), which defines a substantially smooth inner surface 42 extending from the air opening 2 upwardly to the tuyère extension 9. The outer wall plate 41 may be provided with slots 43 and 44, which extend inwardly from side edges 45 and 46 of the curved plate 41. These slots are positioned to coincide with similar sets of apertures 47 and 48 formed in the side-wall flanges 15 and 16, respectively, whereby the outer cover plate 41 may be detachably secured in position by bolts (not shown). A lower edge 51 of the plate 41 may be provided with a depending flange 52 which is apertured to receive bolts 53, so that this end of said plate may be clamped to the furnace wall 1. An upper edge 54 is similarly provided with a horizontal flange 55, whereby the opposite end of the plate 41 may be se-

cured to the horizontal flange 32 of the section having a removable plate provided with a curved interior wall. 41 is thus detachably secured in position.

I further provide the outer curved plate 5 41 with an opening 57 through which access may be had to the interior of the wind-box 5 when it is desirable to clean out the connected parts of the furnace. The opening 57 may be closed by a cover plate 58 which 10 may be clamped in position by means of bolts 59 that engage slotted lugs 61 of said cover plate. The lugs 61 are so disposed that when the bolts 59 are released, the plate 58 may be easily removed. The cover plate 58 may 15 be provided with an aperture 62 which is normally closed by a glass plate 63 and removably secured in position by a ring 64 defining a so-called "peep hole" 65.

While I have shown only one embodiment 20 of my invention, for the purpose of describing the same and illustrating its principles of construction and operation, it is apparent that various changes and modifications may be made therein without departing from the 25 spirit of my invention, and I desire, therefore, that only such limitations shall be imposed thereon as are indicated in the appended claims or as are demanded by the prior art.

30 I claim:

1. A cupola having an air opening, and a wind-box therefor having a discharge end in operative relation to said air opening, said wind-box having a removable plate extending 35 from said air opening, the inner surface of said plate being curved.

2. A furnace wall having an opening, and a wind-box having a section extending from 40 said opening and defining an upwardly curved interior surface, said section including a removable curved plate, one end of which is secured to said furnace wall.

3. A bootleg wind-box having an air inlet 45 end, and a transversely extending discharge end, said ends being inter-connected by a

4. A tuyère elbow constituting one section of an air supply passage, said elbow being provided with an elongated aperture extending from one end thereof, and a curved removable cover for said elongated aperture. 50

5. The combination with a furnace wall, of a wind-box having a discharge end adjacent to said wall, an elbow section of said wind-box having a removable plate extending forwardly and upwardly from said wall, the inner surface of said plate defining a curved wall. 55

6. A tuyère elbow comprising a casting 60 having substantially flat parallel side walls and a curved inner wall, and a curved plate removably secured to said side walls so as to define the outer wall of said elbow.

7. A tuyère elbow comprising a casting 65 having substantially flat parallel side walls and a curved inner wall, a curved plate secured to said side walls, so as to define the outer wall of said elbow, said outer wall having an aperture affording access to the interior of said elbow, and a plate for closing said aperture, removably secured to said outer wall, said plate having a sight hole. 70

8. A tuyère elbow comprising a pair of substantially flat side walls having transversely extending flanges on the outer edges thereof, the inner edges being connected by an integral section constituting an inner wall, and a curved plate removably secured to 75 said flanges so as to constitute an outer wall 80 of said elbow.

9. The combination with a furnace wall, of a tuyère-wind-box comprising an elbow section, and an extension section, said elbow section having a curved plate, the ends of 85 which are provided with flanges respectively secured to said furnace wall and to said extension section.

HARRY W. TITGEN.
